D. S. O'DONOVAN

MUFFLE FURNACE

Filed Feb. 29. 1924

UNITED STATES PATENT OFFICE.

DAVID STANISLAUS O'DONOVAN, OF VOGELOFONTEIN, TRANSVAAL, SOUTH AFRICA, AS
SIGNOR TO O'DONOVAN FURNACES LIMITED, OF JOHANNESBURG, SOUTH AFRICA.

MUFFLE FURNACE.

Application filed February 29, 1924. Serial No. 696,047.

To all whom it may concern:

Be it known that DAVID STANISLAUS O'DONOVAN, British subject, residing at 12 Plantation, Vogelfontein, Transvaal Province, Union of South Africa, has invented certain new and useful Improvements in Muffle Furnaces, of which the following is a specification.

The present invention has reference to muffle furnaces and more particularly to such furnaces in which a series of muffles (or an equivalent long muffle) is arranged in a long flue or heating chamber so as to be heated to progressively differing temperatures, whereby articles placed in the muffles and shifted step by step through the series are subjected to gradual heating.

The purpose of the invention is to enable the heat gradient in the muffle series to be adjusted as required, more particularly by relatively raising the temperature at the cooler end of the series, which tends to become unduly cool.

The invention is illustrated in the accompanying drawings in which—

Fig. I is a longitudinal section of a furnace, and

Fig. II is a transverse section on II—II, Fig. I.

The source of heat is indicated by a firebox 2 situated at one end of the furnace structure 3. 4 is a flue leading from the fire box and 5 a long muffle chamber disposed parallel with the flue. Muffles 6 are supported in the wall of the muffle chamber and project transversely into said chamber. Their inner ends are closed and their outer ends open to receive the articles to be heated e. g. rock drill tools 11.

The muffles are arranged in a row or rows; the said row or rows, together with the muffle chamber and the flue, being preferably disposed horizontally so that a number of drills or other bodies positioned in the muffles are convenient of access for shifting them step-by-step through the muffle series.

Two horizontal rows (6^a to 6^b and 6^c to 6^d) of muffles are shown, projecting in from opposite sides of the furnace structure and positioned one above the other.

The division between the flue and the muffle chamber is provided by a number of fire-brick slabs 7. These rest on corbels 8 and can be slid along the same to any de-

sired positions and provide openings such as 9, 9^a, 9^b, etc., for the furnace gases to pass from the fire box and the flue to the muffle chamber. The used gases pass away by a chimney 10 distant from the fire box 2.

The general effect of passing the furnace gases through the series of muffles from the source of heat disposed at one end of the series, is to establish a temperature gradient throughout the series, the muffles 6^a, 6^c most distant from the fire being least heated, and the temperature increasing up to the muffles 6^b, 6^d nearest the fire, which attain the highest temperature. Accordingly an article placed first in the muffle 6^a or 6^b and then shifted at intervals into each of the muffles of its row, is heated to the final temperature gradually without being exposed at any time to a temperature excessively higher than its own, which would tend to deteriorate its structure. It is preferred to use a large number of muffles in each series, both in order that the temperature steps should be small and also to enable the metal articles to be treated in considerable numbers without forcing the rate of heating.

The various openings which conduct the hot gases into the muffle chamber are so adjusted that whilst a substantial proportion of the furnace gas passes directly into the muffle chamber through the relatively large opening 9, other proportions of the gas are fed in at different openings 9^a, etc., farther away from the fire, to reinforce the heating effect in the chamber at those points; such reinforcing gases having been but little cooled in comparison with the directly admitted gases which have already passed through some of the muffle series.

It is advantageous to position the muffles closely, together thereby setting up a material resistance to the gas flow which is utilized to adjust the gas distribution as desired.

The effect is to relatively raise the temperature of the cooler parts of the muffle series, and it is possible in this way to so adjust the temperature gradient throughout the series, as to attain the maximum speed of movement of the articles through the furnace, whilst exposing them to the minimum temperature increments at each step. It is evident that articles which have been heated and require to be cooled at a regulated rate

may be passed through a similar muffle series in the reverse direction with similar advantageous results.

It is found that with a furnace constructed as shown in the drawings the temperature gradient may be varied by increasing or decreasing the draft and at the same time readjusting the openings 9, 9^a, etc., without materially varying the final temperature exhibited by the muffles. When the character of the work to be done varies from time to time, the slabs are arranged adjustably as shown; but it will be evident that for carrying out operations of an unvarying character, the slabs may be permanently positioned to provide the reinforcing openings required.

I claim:—

1. A muffle furnace comprising a muffle chamber, a source of heated gas feeding the muffle chamber so as to produce a temperature gradient therein, muffle means arranged in the muffle chamber to be heated to different temperatures corresponding to the temperature gradient, there being a direct inlet for gas from the source to one end of the muffle chamber and at least one indirect inlet modifying the temperature gradient which the directly admitted gas tends to produce.
2. A muffle furnace comprising a single source of heated gas, a long muffle chamber through which gas from the source passes (in substantially one direction) whereby a temperature gradient is set up in the chamber, a flue fed from the source and means

affording communication from the flue to the chamber for passing reinforcing supplies of gas from the flue into the muffle chamber.

3. In a muffle furnace, a source of heated gas, a long muffle chamber fed at one point directly from said source, a chimney arranged to exhaust the whole of the gas from a point in the muffle chamber distant from the point at which the gas is fed thereto, a flue fed by said source, and means affording communication between the flue and the muffle chamber for passing supplementary supplies of gas into the latter.

4. In a muffle furnace, a source of heated gas, a muffle chamber, a flue parallel with the same and movable means providing adjustable openings from the flue to the chamber.

5. In a muffle furnace, a source of heated gas, a muffle chamber, a flue beneath the same, slab supports and slabs loosely carried on said supports and interposed between the flue and the chamber.

6. In a muffle furnace, a fire box, a long horizontal muffle chamber fed at one end directly from said fire box a chimney at the other end of the chamber, a series of muffles extending through the chamber wall transversely into the chamber, a flue beneath the chamber and slabs separating the flue from the chamber.

In testimony whereof I affix my signature.

DAVID STANISLAUS O'DONOVAN.
